UNITED STATES PATENT OFFICE.

CHARLES W. A. ZADEK, OF BARTOW-ON-THE-SOUND, NEW YORK.

EXPLOSIVE COMPOUND.

SPECIFICATION forming part of Letters Patent No. 335,006, dated January 26, 1886.

Application filed October 7, 1885. Serial No. 179,210. (No specimens.)

To all whom it may concern:

Be it known that I, CHARLES W. A. ZADEK, of Bartow-on-the-Sound, in the county of Westchester and State of New York, have 5 invented certain new and useful Improvements in Explosive Compounds, of which the following is a specification.

This invention relates to an improved explosive compound for mines, torpedoes, and 10 projectiles; and it consists of an explosive compound formed of a mixture of resinate of calcium or magnesium and trinitro-glycerine. The resinates are prepared as follows: A sufficient quantity of caustic soda is dissolved at 15 boiling heat in an iron kettle, and as much colophony added thereto as the caustic soda can absorb. This solution is drawn off and strained and then allowed to cool. On the cold mass is poured a not too concentrated 20 solution of chloride of calcium or sulphate of magnesium. The precipitate formed is a resinate of calcium or magnesium, according as the calcium or magnesium salt has been used. The resinate is thoroughly washed and then 25 collected, pressed out, and separated in a centrifugal machine from the adhering water, then dried on linen-covered frames at a temperature of 50° Reaumur, and finally pulverized, so that an impalpable powder is obtained which 30 possesses the property of mixing readily with nitro-glycerine, and to form therewith a jelly-like mass when mixed in proportions of twenty-five parts of the resinate to seventy-five parts of nitro-glycerine. With a greater 35 quantity of resinate—say, from twenty-five to sixty in one hundred parts—nitro-glycerine forms a more or less glutinous mass, which can be handled easier and with less danger than any other mixture of nitro-glycerine.

The disadvantages of all known mixtures 40 of nitro-glycerine consists in their sensitiveness to accidental shocks or concussions with other bodies. This sensitiveness is entirely avoided by my compound, as the same possesses greater elasticity, and is thereby better 45 adapted for torpedoes and projectiles. The same can be manufactured without danger and is not affected by water. It is discharged by means of caps containing fulminate of mercury. It is free of gases injurious to the 50 lungs, as the formation of carbonic-acid gas is greatly reduced, whereby the compound is adapted for use in closed spaces, such as mines, &c.

Another special advantage of my improved 55 explosive compound is that it does not crystallize when cooled down to the freezing-point or even at a lower temperature. At a temperature of 20° to 30° Fahrenheit the compound assumes a granular form of extreme 60 fineness, in which state it is not impaired in the least for practical use and can be handled with safety.

Having thus described my invention, I claim 65 as new and desire to secure by Letters Patent—

An explosive compound consisting of a mixture of resinate of calcium or magnesium with trinitro-glycerine, substantially as set forth.

In testimony that I claim the foregoing as 70 my invention I have signed my name in presence of two subscribing witnesses.

CHARLES W. A. ZADEK.
